UNITED STATES PATENT OFFICE.

DAVID MICON, OF BENTON HARBOR, MICHIGAN.

MATTRESS.

Application filed May 15, 1920. Serial No. 381,591.

To all whom it may concern:

Be it known that I, DAVID MICON, a citizen of the United States; residing at Benton Harbor, in the county of Berrien and 5 State of Michigan, have invented certain new and useful Improvements in Mattresses, of which the following is a specification.

The general object of this invention is to provide a mattress simple in construction, 10 attractive in appearance, and which may be produced at a relatively small cost.

The invention relates particularly to mattresses of the kind set forth in my Patent No. 1,211,475 patented January 9, 1917, 15 provided with rolls along the upper and the lower edges of the body portion. The primary purpose of such mattresses is to produce a neat appearing bed and to accomplish this, it is essential that all rough or 20 protruding edges be eliminated where possible.

With the present high cost of labor, and the difficulty of securing skilled operators, it is particularly important to avoid as far 25 as possible all unnecessary operations and to so design the construction that the use of skilled labor in its manufacture is unnecessary. Therefore, one of the objects of the present invention is to eliminate as 30 many seams as possible, and to permit the tick to be substantially completed before the filling is placed therein.

Another object is to provide the mattress with roll edges having suitable and 35 seamless outer faces to present an attractive appearance and avoid wear and breaking.

My invention and its numerous objects and advantages will be better understood 40 by reference to the following specification when read in connection with the accompanying drawing in which—

Fig. 1 is a perspective view of a portion of a finished mattress,

45 Figs. 2 and 3 are detail sectional views illustrating one method of manufacture of the invention,

Fig. 4 is a vertical, sectional view of a portion of the mattress made in the manner 50 disclosed in Figs. 2 and 3.

Fig. 5 is a detail sectional view illustrating the method of manufacture of a modified form of the invention,

55 Fig. 6 is a vertical section of the mattress made in the manner disclosed in Fig. 5.

Fig. 7 is an enlarged detail view illustrat-

ing the method of forming the corners of the roll.

Fig. 8 is an enlarged perspective view 60 of one corner portion of the mattress.

Referring to the drawings, 10 indicates the top, 11 the bottom and 12 the border of the tick which may be filled with hair, felt or any suitable material or combination of materials suitable for the purpose. At the 65 edges of the top and bottom of the tick the edges of the top and bottom of the tick the rolls 13 and 14, respectively, are formed.

The method of manufacture of the tick, in the embodiment shown in Figs. 2 to 4 inclusive, is illustrated in Figs. 2 and 3. 70

The top 10 of the tick is laid out flat and the strip which is to form the roll edge is laid inverted thereon with its outer edge projecting about one-third of its width beyond the edge of the top of the tick as indicated in solid lines in Fig. 2. The top and strip are then sewed together at 15. The inner edge of the roll strip 13 is now turned over on its outer edge in the manner indicated in broken 80 lines in Fig. 2, and the border strip 12 inverted is placed thereon with its edge coincident with the edges of the roll strip, in the manner illustrated in Fig. 3. The two edges of the roll strip 13 and the edge 85 of the border strip 12 are now sewed together at 16. The bottom roll is formed on the bottom of the tick and secured to the border strip in the manner described in forming the top roll except that the parts 90 are laid out turned in the opposite direction as will be readily evident.

In order to make smooth and rounding corners, I have found it advantageous to 95 cut notches 17 in the roll strip in the manner shown in Fig. 7 and then to draw together and stitch the edges of the notches to produce the corner effect shown in Fig. 8 in the drawing.

In the modified form of the invention 100 shown in Figs. 5 and 6 the border 18 is laid upon the top 19 and a portion of the top is turned over onto the border to form an end flap 20, as shown in solid lines in Fig. 5, and the three layers are stitched together at 21. 105 The border 18 and the end flap 20 are now turned into the position indicated in broken lines in Fig. 5 and these two layers are stitched at 22. In turning the border 18 in the manner described, sufficient fullness 23 110 should be allowed to form the roll. The lower roll edge is formed in the same way

cept that the parts are laid out reversely as will be readily understood. In this modification of the invention it will be seen that the border 18 forms the outer wall of the roll 5 and the inner wall is a continuation of the top or bottom of the tick as the case may be. In this form as in the previous embodiment, the outer wall of the roll is smooth and without seams or ridges, presenting a neat, and 10 attractive appearance.

My invention materially reduces the time and labor involved in preparing the tick for a roll edge mattress. The rolls may be filled in accordance with the invention set forth in 15 my application Serial No. 366,106 filed March 15, 1920, or in any other suitable manner.

Changes in the form, construction and arrangement of the parts may be made without departing from the spirit of the invention or sacrificing any of its material advantages, and I reserve the right to make all such changes as fairly fall within the scope of the following claims.

25 I claim:

1. A mattress comprising a tick having a top, a bottom and a border, strips of material formed into separate rolls with the edges of each strip stitched together and to an edge 30 of the border, one of said rolls having an intermediate portion stitched to the edge of the top and the other roll having an intermediate portion stitched to the edge of the bottom, and filling for the tick and the rolls.

35 2. A mattress comprising a tick having a top and a separate border, a separate strip of material stitched between its edges to the edge of the top, the edges of the strip being stitched together and to an edge of the 40 border to form a roll, and filling for said roll.

45 3. A mattress tick having an edge roll consisting of a strip having its edges secured together and to an edge of one of the walls of the tick, and an intermediate portion of the roll being secured to an edge of an adjacent wall of the tick.

50 4. A mattress tick comprising separate top, bottom and side walls, an edge roll consisting of a separate strip having its edges secured together and to an edge of one of the walls of the tick by one and the same securing means, an intermediate portion of the

roll being secured to an edge of another wall of the tick, said strip having substantially V-shaped notches at each of the four corners of the tick, the walls of each notch being drawn together to form a rounded bend in the edge roll at each corner of the tick. 55

5. In the making of a mattress tick, the steps of securing an intermediate portion of 60 a roll strip to the edge of a tick section, folding said roll strip to bring its edges together, and securing said edges to the edge of another tick section.

6. In the making of a mattress tick, the 65 steps of placing a roll strip upon a tick section with the roll strip projecting outwardly beyond the tick section, stitching an intermediate portion of the roll strip to said edge of the tick section, folding the roll strip to 70 bring its edges together outwardly beyond the edge of the tick section, placing an edge portion of another tick section upon the roll strip at the outer edge thereof, and stitching together the edges of the roll strip to the 75 said other tick section.

7. The method of making a mattress tick which consists in sewing an intermediate portion of a strip to the edge of the top section, folding the strip to bring the edges 80 thereof together, sewing the edges of the strip to the upper edge of the border section; sewing an intermediate portion of a second strip to the edge of the bottom section, folding the second strip to bring its edges together and sewing the edges of the second strip to the lower edge of the border. 85

8. The method of making a tick for a mattress which consists of laying the top section with the outer surface upward, laying a 90 strip with its outer surface downward on the edge of the top section, sewing an intermediate portion of said strip to the edge of said top section; folding the inner edge of the said strip upon the outer edge thereof, laying 95 the border inside out with its upper edge flush with the edges of said strip and sewing the edges of said strip and said border portion together; folding the border in its entirety outwardly and downwardly, securing a similar strip in the same way to the bottom section and sewing its edges to the free edges 100 of said border.

DAVID MICON.
